U.S. PATENT DOCUMENTS

The ornamental design for a support base for an electric device such as a computer, TV controller, video game machine, or audio or video disc player, as shown and described.

DESCRIPTION

- D. 270,026 * 8/1983 Whitford .
D. 287,365 * 12/1986 Judd .
D. 330,021 * 10/1992 Kline et al. .
D. 330,705 * 11/1992 Gowda et al. .
D. 338,882 * 8/1993 Reiter .
D. 349,696 * 8/1994 Hames .
D. 350,536 9/1994 NcKnight et al. D14/114
D. 361,561 * 8/1995 Baudot .
D. 362,245 * 9/1995 Moffatt .
D. 383,728 9/1997 Yurkonis et al. D14/100

FIG. 1 is a perspective view of a support base for an electric device such as a computer, TV controller, video game machine, or audio or video disc player showing my new design, on a reduced scale;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
